Primary Examiner — Katrina A Betton(57) **CLAIM**

The ornamental design for a holiday fountain cover, as shown and described.

DESCRIPTION

FIG. 1 is a perspective front view of a holiday fountain cover;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken lines shown in the drawings that illustrate a fountain form no part of the claimed design.
